(57) **CLAIM**

The ornamental design for an electronic cigarette power supply, as shown and described.

DESCRIPTION

FIG. 1 is a top, front and left perspective view of my new design for an electronic cigarette power supply.

FIG. 2 is a top, back and right perspective view.

FIG. 3 is a right side view. The left side view is a mirror image of the right side view.

FIG. 4 is a top view. The bottom view is a mirror image of the top view.

FIG. 5 is a front view; and,

FIG. 6 is a back view.

The portions of the drawings shown in dashed broken lines form no part of the claimed design.

1 Claim, 2 Drawing Sheets

FIG. 6
